(57) **CLAIM**

The ornamental design for a knife with a rifle stock handle, as shown and described.

DESCRIPTION

FIG. 1 is a top right perspective view of a knife with a rifle stock handle showing my new design, looking from the tip to the butt;

FIG. 2 is a bottom right perspective view thereof, looking from the butt to the tip;

FIG. 3 is a right side elevational view thereof, showing an increasing taper from the hilt to the butt;

FIG. 4 is a top plan view thereof, showing a waist portion between the hilt and the butt;

FIG. 5 is a left side elevational view thereof, also showing an increasing taper from the hilt to the butt;

FIG. 6 is a bottom plan view thereof, also showing a waist portion between the hilt and the butt;

FIG. 7 is a tip end elevational view thereof; and,

FIG. 8 is a butt end elevational view thereof.
